UNITED STATES PATENT OFFICE.

JOHN PLATT, OF HARROW, ENGLAND, AND WILLIAM PLATT AND HENRY PLATT, OF ROUBAIX, FRANCE.

CARDING MACHINE.

Application filed June 23, 1925, Serial No. 38,952, and in Germany July 1, 1924.

This invention relates to carding machines and has particular reference to that part of the machine which comprises the carding rollers or organs known as the swifts and doffers, which are covered with a clothing comprising a leather or fabric and rubber foundation into which are set staples made of fine steel pointed wire of bent or knee formation for the purpose of parallelizing the fibres of cotton, worsted and wool and other textile fibres. This form of card clothing which will be hereinafter referred to as the ordinary card clothing is universally used on the swifts, workers or flats and doffers of all carding machines, which are of course distinct from machines known as waste openers or "Garnett" machines, wherein the rollers are usually covered with serrated or saw toothed wire on which the teeth are strong and coarse for opening up the material prior to carding. During the carding of fibres in the carding machine the material tends to accumulate at the bottom of the teeth owing to the bent or knee shaped form of the latter and this accumulation increases until it reaches the points or outer ends of the teeth when it becomes necessary to stop the operation of the machine in order to remove the accumulation which is generally called the "stripings" or "fettlings." This cleaning or fettling operation has to be effected after the machine has been running for a comparatively short time, and consequently the output of the carding machine is somewhat restricted.

The object of the present invention is to avoid or reduce this accumulation of the material on the swift and doffer so that a much longer uninterrupted operation of the carding machine can be effected. This is accomplished according to the present invention by using in conjunction with a swift clothed with the ordinary card clothing, a doffer which is clothed with a wire wound round the same and provided with rigid, slender teeth that taper from base to point so that they are of needle like formation without any bend or kink such as exists in the teeth of the ordinary card clothing.

This form of clothing on the doffer provides a series of straight needle-like teeth which are set at an angle and enable the material to be easily thrown off and removed by the doffing comb during the revolution of the doffer so that the latter is at

all times free or clear of accumulation and can take up or receive the material from the swift, with the result that the swift is automatically maintained clear of accumulation, thereby eliminating the necessity of frequent stoppages of the machine for cleaning the swift and doffer so that the carding operation can be effected continuously for much longer periods than heretofore, thus substantially increasing the output of the carding machine. In addition to this important advance in the art, the material removed by the doffing comb is cleaner and more satisfactorily carded, as the nips, dirt, etc. are more easily thrown out through the grids under the rollers owing to the teeth on the swift and the doffer being maintained free or clear of accumulation. By this invention we can produce a more even film and greater regularity in the silver which is a matter of considerable importance.

In order that the present invention may be more clearly understood and readily carried into effect, the same will now be more fully described with reference to the accompanying drawings, in which:

Figure 1 illustrates diagrammatically so much of a well known type of a cotton carding machine as is necessary for a proper understanding of this invention.

Figure 2 is an enlarged fragmentary diagrammatic view showing portions of the swift and doffer clothed according to the present invention.

Figure 3 is an enlarged side view of a portion of the card clothing wire provided on the doffer according to this invention.

Figure 4 is a fragmentary sectional view showing several convolutions of the clothing wire on the doffer according to this invention.

Figures 5 and 6 are respectively an end view and an elevation of the doffer illustrating the manner in which the clothing wire is applied thereto.

Referring to Figure 1, A, A represent the feeding rollers which supply the raw cotton or other material to the licker-in roller B which as usual is covered with coarse teeth for effecting the opening of the more or less clotted or matted material and supplies the opened material to the cylinder or swift C. In the example shown D, D represent carding flats which are provided with the ordinary form of card clothing for co-oper-

ating with the ordinary card clothing on the swift. Instead of employing carding flats as shown, rollers known as workers and covered with the ordinary card clothing may 5 be employed for co-operating with the swift as is done for the woolen and worsted carding engines. E indicates the doffer which receives or takes the material from the swift C, the material being afterwards taken from 10 the doffer by the doffing comb F and finally coiled out as indicated at G. The general arrangement as shown in Figure 1 is of course quite a usual one and does not require detailed description, but as the invention is 15 concerned with the co-operation of the swift C and the doffer E, the operation which takes place with regard to these two rollers will now be more fully described. For this 20 purpose it is necessary to refer more fully to the ordinary form of card clothing which is provided on the swift and heretofore on the doffer, so that the difficulties and objections which exist in machines at present in use and the means provided according to 25 this invention for overcoming the same can be readily appreciated. The ordinary form of card clothing at present in use on both the swift and doffer is represented in Figure 2 by C¹. In Figure 2 C¹ represents the 30 teeth and C² indicates the rubber and fabric or other soft foundation in which the teeth are set. The teeth are bent near their lower parts for cotton carding (and at the middle for worsted carding) so as to have 35 a kind of knee shaped formation as indicated at C³. In practice, the teeth are oppositely directed or inclined on the swift and the doffer so that during the revolution of the swift and the doffer in the directions shown 40 by the arrows in Figure 1, the doffer which rotates slower than the swift can take the material from the swift and carry it to the doffing comb F which removes it so that it can be coiled out as shown at G. As the 45 carding operation continues some of the material which slips down to the bottom of the teeth below the bend C³ tends to remain there as the bend holds it and as the doffing comb G works at the face or outer ends of the 50 teeth and not at the bottom, it cannot remove this material which therefore starts accumulating at the bottom of the teeth. As the material accumulates on the doffer the latter becomes less and less able to take the material 55 from the swift. During the revolution of the swift the material which escapes the operation of the doffer is carried round on the swift so that it meets the material which is supplied by the licker-in roller B. The material which has escaped the doffer 60 tends to be forced towards the bottom of the teeth on the swift by the new material supplied and fed over it by the licker-in roller so that it is carried round on the swift 65 under the new material in the form of a

layer to the flats or workers, then again to the doffer and so on. This accumulation on the swift becomes thicker and thicker until it eventually reaches the points of the teeth which become clogged with matted material, 70 nips, dirt, etc., entangled with the new fibres fed over them, thus adding to the difficulty of stripping by the doffer. It is evident that when both the clothing on the swift and doffer has become clogged to this extent 75 good carding is impossible. At this stage, which occurs after about three hours working when carding cotton and after about forty eight hours when carding worsted, the machine has to be stopped to enable the 80 swift and the doffers to be cleaned or fettled, thus restricting the output of the machine, whilst time and labour are wasted in performing the cleaning operation which can practically be avoided by the present invention, so that a practically continuous carding 85 operation can be effected with better results as both the swift and the doffer remain clear of accumulation of the fibres, dirt, nips, etc., 90 during the running of the machine and during the actual carding operation.

The objections above referred to with regard to the existing machines are overcome according to the present invention by employing in conjunction with a swift clothed with the ordinary card clothing, a doffer on which is substituted for the ordinary card clothing, a clothing which not only prevents accumulation on the doffer but also automatically maintains the ordinary card clothing on the swift clean and free from accumulation during the operation of the machine. For this purpose the doffer is 95 covered with a clothing in the form of a continuous length of wire H which is wound round the doffer and is formed with straight rigid teeth H¹ inclined in the same direction, the teeth being slender and tapering from base to point as shown in Figures 3 and 4, so that they are much higher than the width 100 of their bases, as shown in Figure 3, and may be regarded as needle like teeth. The wire foundation K is slightly thicker than the teeth K¹ as shown in Figure 4 so as to provide an offset portion which serves as a 105 spacing piece to maintain the circumferential rows of teeth a short distance apart when the wire is wound round the doffer in a continuous length as shown in Figures 5 and 6. The peripheral surface of the doffer 110 is plain, that is ungrooved, so that the various convolutions of the wire H can be wound on the said surface to lie in contact with each other as shown in Figure 4, with the result that owing to the large number 115 of teeth which are provided per linear inch on the wire a considerable number of points or teeth per square inch can be obtained and the number may be equal to or may exceed, 120 the number of points per square inch pro- 125

- vided in the ordinary card clothing. For instance, as many as 450 to 600 points per square inch, according to the nature of the raw material to be carded can be provided 5 in the clothing on the doffer according to this invention. It will be therefore understood that in addition to the close disposition of the teeth along the length of the wire, the wire itself must only slightly exceed the thickness of the teeth to enable the 10 desired number of teeth to be provided on the doffer whilst at the same time affording sufficient room for the fibres to pass down the teeth between the circumferential rows. 15 As the teeth are rigid when the wire is wound on the doffer and owing to the fact that they are straight as distinct from knee shaped formation, the material is not held back in any way on the doffer, which therefore 20 can be readily stripped or cleared by the doffing comb; the angle at which these rigid and straight teeth are set also assists in the material being readily removed by the doffing comb. The doffer clothed in 25 this manner therefore not only remains clear of strippings, dirt, nips etc., but immediately and continuously clears the swift which is covered with the ordinary card clothing, this being due to the fact that the teeth on 30 the doffer are always clear and therefore are free to take all the material which is presented to it by the swift, which is not the case in the old system. As a matter of fact, the doffer according to this invention would, 35 if placed in a machine having a swift full
- of strippings and settings, immediately start to clear the swift. By the present invention a carding machine can be operated for long periods without stoppages for cleaning the swift and doffer owing to the 40 automatic cleaning effected by the doffer clothed with the card clothing wire herein described, and in addition to increasing the output of the machine the material is carded more satisfactorily as dirt, nips, etc., can 45 be more readily thrown out owing to accumulation of the fibres on the teeth being avoided. The present invention also avoids the use of expensive vacuum stripping machines and other machines used for stripping and cleaning the rollers. 50

What we claim and desire to secure by Letters Patent of the United States is:—

1. In a carding machine, the combination with a swift clothed with the ordinary card clothing of a doffer which is clothed with a clothing comprising straight and rigid teeth that taper from bottom to top to provide needle-like points. 55
2. In a carding machine, the combination with a swift clothed with the ordinary card clothing, of a doffer clothed with a clothing in the form of a wire which is wound round the doffer and is provided with a straight and rigid teeth that taper from bottom to 60 top so as to provide needle-like points. 65
